(57) **CLAIM**

The ornamental design for a hanging fish attractor, as shown and described.

DESCRIPTION

FIG. 1 is a perspective view of the hanging fish attractor; FIG. 2 is a left side view of the same, the right side being a mirror image;

FIG. 3 is a front elevational view of the same, the rear elevational view being a mirror image;

FIG. 4 is a top plan of the same;

FIG. 5 is a bottom plan view of the same; and,

FIG. 6 is an environmental view of the same.

The broken lines in FIGS. 1-6 illustrate portions of the hanging fish attractor that form no part of the claimed design. Additional dashed lines in FIG. 6 illustrate environment and form no part of the claimed design.

1 Claim, 5 Drawing Sheets
